ENGLAND

CONVEYANCE OF GOODS THROUGH FURNACES AND THE LIKE

Application filed December 24, 1930, Serial No. 504,562, and in Great Britain October 8, 1930.

This invention has reference to certain improvements in connection with the conveyance of goods through furnaces and the like.

5 In the various methods hitherto applied for this purpose, including the use of endless conveyors which carry the work, rotary discs which form a series of live rollers, and also what is known as the reciprocating bar or 10 "walking beam" by which the goods progress step by step through the furnace but remain stationary during the return stroke of the bars, various inconveniences and disadvantages have been experienced. The 15 endless conveyor method for instance has necessitated the heating of the conveyor parts in addition to the goods treated; the roller disc method has necessitated high power, and also boxes or carrier sheets for the goods; whilst the walking beam arrangement involves the use of stationary members 20 for supporting the load during the return stroke of the reciprocating bars and has therefore necessitated constant picking up 25 and putting down of the load.

The present invention is designed to avoid these and other inconveniences and disadvantages, and to provide an improved method and means of conveyance which shall be 20 particularly reliable and efficient and which shall therefore tend to a higher degree of efficiency in the operation of the furnace or the like.

The invention consists in a method and 35 means of conveying goods on a reciprocating bar conveyor, characterized in that the bars are arranged in alternated series which are each adapted for movement both at normal level and at a lower level, and further characterized in that each series of bars is lifted 40 to and lowered from its load-carrying level only when moving at the same synchronized forward speed as the alternated series of bars, whereby the load is transported uniformly and uninterruptedly by the conveyor 45 without any relative or differential movement between the load and the carrier bars in the direction of load traverse.

50 A further feature of the invention is that the alternated series of carrier bars are

mounted upon separate supports the rising and falling movements of which are controlled by timing mechanism geared to the mechanism which reciprocates the bars, these supports preferably consisting of cross girders disposed in balanced pairs on rocker arms which are connected in series to the timing mechanism.

In order that the invention may be clearly understood and readily carried into practice, 60 reference may be had to the accompanying explanatory sheets of drawings, in which:—

Figures 1, 1a, and 1b together constitute a side elevation of the invention as applied by way of example to a furnace employed for 65 continuous heating or heat treatment of metal sheets, bars, axles, and the like, the view being partly in section and being brought within reduced longitudinal limits 70 by the omission of certain intermediate parts.

Figure 2 is a plan of Figure 1.

Figure 3 is a sectional end elevation of the furnace, the section being taken on a plane indicated by the line III—III of Figure 1a. 75

Figure 4 is a perspective view showing details of the rocker and balanced girder mechanism for elevating and depressing the two alternated series of reciprocating bars constituting the moving hearth of the furnace, the view being in section likewise taken on a plane indicated by the line III—III of Figure 1a, with parts of the furnace setting omitted for facility of illustration.

85 Figure 5 is a partly sectional side elevation of the mechanism for controlling the reciprocation of the two alternated series of bars and for controlling and timing their balanced rising and falling movements.

90 Figure 6 is a plan of the mechanism shown in Figure 5, but with the casing cover removed.

95 In one method of carrying the invention into effect, as applied in connection with a furnace of the kind illustrated and hereinbefore referred to, the hearth of the furnace is constituted over the whole or the greater part of its width by longitudinally reciprocating bars arranged side by side in 100

two alternated series 1 and 2 extending throughout the preheating chamber 3, the main heating chamber 4, the cooling chamber 5, and the loading and unloading extensions 6 and 7 at opposite ends, the one series of bars being movable in a forward direction whilst the other series of intermediate alternated bars are completing the return stroke at a slightly lower level. The mechanism is so arranged that whilst the metal sheets or goods are making forward progress on the one alternated series of bars at the higher level, the intermediately alternated bars complete their backward stroke and also reverse and assume a forward velocity equal to that of the bars which for the time being are carrying the load, and after assuming such equal velocity these intermediate bars rise and take the load from the first-mentioned series of bars, which are then approaching the end of their forward stroke in readiness for the same return cycle at the lower level as the intermediate bars which have just assumed the carrying of the load and which continue to move forward at the higher level until they in turn reach the end of their stroke. By this means the goods under treatment move constantly, uniformly, and uninterruptedly through the entire length of the furnace and its associated cooling chamber. The speed of movement of the bars 1 and 2 in a load-carrying direction need never exceed the normal rate of travel of the goods through the furnace, whereas in the case of the intermittent walking beam type of conveyor it has been necessary for the bars to assume a speed greatly in excess of the average speed of the goods through the furnace.

The alternated series of reciprocating bars 1 and 2 are furnished, on the parts located within the heating chamber 4 and preheating chamber 3, with interlocking refractory heat-resisting blocks 8 having dovetailed attachments to the bars, or the bars may be provided alternatively with heat-resisting metallic facings. By means of these blocks a refractory high-temperature hearth is provided which allows for the propulsion of either heavy or light loads, which provides an insulated bed and avoids abrasion or damage to the materials conveyed, and which at the same time eliminates heating of the mechanism as the load is heated, thus giving much higher efficiency and ensuring effective protection for the goods under treatment. The arrangement moreover is such that subject to very slight clearance the bars facilitate the provision of virtually a solid hearth.

The mechanism employed for reciprocating the two alternated series of bars 1 and 2 is connected by a timing gear to the mechanism which elevates and depresses one or other series of the bars at such times as the

two series of bars are synchronous in their forward velocity, either shortly after the beginning or shortly before the end of the forward stroke. For this purpose the drive is taken from a variable-speed motor 9, through a speed-reducing gear 10 and a reciprocating gear box 11, from which the drive is transferred to the respective series of bars 1 and 2 by means of a cam roller 12 mounted on the main shaft and having a cam groove 13 into which a pair of ball-bearing rollers 14 and 15 are engageable on diametrically opposite sides of the cam roller, these rollers 14 and 15 being carried by an opposite pair of crossheads 16 and 17 having link connections 18 and 19 to a pair of cross girders 20 and 21 to which the forward ends of the two series of bars 1 and 2 are respectively attached, the form of the cam groove 13 determining the stroke of the bars and being such that the driving cam roller 12 imparts a precise forward movement at absolutely uniform speed when the bars are in load-carrying position, with a necessarily faster return movement, and as the same cam groove 13 controls both series of bars, it follows that there can be no variation in speed as between the two series of bars 1 and 2.

The two alternated series of carrier bars 1 and 2 are supported at suitable spacings on heavy cross girders 22 and 23 arranged in pairs, each girder supporting alternate lines of bars. These girders 22 and 23 are slidably supported by means of small rail tracks 24 upon adjustable ball-bearing wheels 25 mounted on the opposite ends of rocker arms 26 arranged in pairs on opposite sides of the furnace, by which means each pair of girders 22 and 23 is automatically self-balancing. The pairs of rocker arms 26 are interconnected in series by means of levers 27 and links 28, 29, and 30 having intermediate double-armed connecting levers 31, the link 28 being jointed at 32 to an oscillating frame 33 the movement of which is controlled by a cam 34 mounted on a countershaft 35 which is driven by bevelled gear 36 from the shaft 37 carrying the main driving cam roller 12.

It will be seen that by thus arranging the reciprocating mechanism in timing association with the balancing mechanism, it follows that if the timing gear is brought into operation only at the critical points in the strokes of the bars, where both series of bars are moving forward at uniform and absolutely synchronized speed, the movement of the rocker arm 26 by the timing gear automatically transfers the load from one series of bars to the intermediately alternated series of bars in precisely the same way as if there were no reciprocating motion at all and the bars were merely alternately up and down with a maximum

stroke of say one inch. That is to say, there can be no differential action, friction, or abrasion as between the load and the respective carrier bars, as transference of the 5 load can only and does only take place at such times as the whole of the bars are moving forward at the critical and constant speed of the load, these conditions being due to absolute interlocking of the reciprocating 10 mechanism with the timing or lifting mechanism.

The reciprocating and timing mechanism is also so disposed as to permit of reversal of the direction of travel of the goods 15 through the furnace, this arrangement being of particular service in the application of the invention to a single-ended chamber, where the load requires to be admitted in one direction and, after necessary treatment, 20 to be discharged from the chamber in the opposite direction. Moreover the bars instead of being straight may be appropriately curved so that the system may be adapted for the conveyance of goods through circular 25 chambers.

The furnace hereinbefore described has the following important advantages:—

(a) The metal sheets or goods are heated without the introduction of dead load (hitherto usually of highly expensive heat-resisting metal), this arrangement with proper combustion conditions, giving the maximum thermal efficiency attainable.

(b) All mechanism is eliminated from the 25 heat zone, so that ordinary means of lubrication are practicable without water-cooling or other means which extract heat from the furnace proper.

(c) The transference of the goods is 40 effected in such a manner as to eliminate the possibility of scratching or surface marking, thereby avoiding the use of carrier sheets, carrier bars, or trays.

(d) The means of transportation or conveyance is of such a character as to enable 45 sheets or other goods of either the lightest or the heaviest gauge to be handled with equal facility and efficiency.

(e) There is no restriction in the length 50 of the goods to be handled, and where a wide hearth area is used the same is adapted to accommodate for instance two narrow sheets, thus utilizing the whole of the hearth area.

(f) The conveying mechanism is of such a 55 form that, when sheets are being handled, the maximum degree of flatness is ensured even in the case of light gauges, so that no sagging or consequent buckling of the sheets can occur.

(g) The speed of conveyance is readily adjustable to suit the requirements and characteristics of the load.

(h) By reason of the form and disposition 60 of the conveying mechanism, the labor

and cost of maintenance is reduced to a minimum, being due only to ordinary mechanical wear of the bearings operating under cool conditions.

(i) The through put capacity of the furnace 70 is very substantially increased without any corresponding increase either in fuel consumption or in the effective hearth area.

It will be understood that the constructional features of the conveyor may be appropriately varied, particularly as regards the balancing or mounting of the reciprocating bars and the timing of their movements, without departing from the scope of the invention as expressed in the appended 75 claims.

It will moreover be appreciated that the improved system is applicable to the transportation or conveyance of goods for treatment or disposal otherwise than by heating, 80 such for instance as for chemical treatment, or solely for conveyance.

We claim:

1. A conveyor of the reciprocating bar type, comprising alternated series of carrier 90 bars each adapted for movement at normal level and at a lower level, in combination with mechanism whereby each series of bars is lifted into and lowered from its load-carrying level only when moving at the same 95 synchronized forward speed as the other alternated series of bars, thus enabling the load to be transported uniformly and uninterruptedly by the conveyor without any relative or differential movement between 100 the load and the carrier bars in the direction of load traverse.

2. A conveyor of the reciprocating bar type, comprising two alternated series of carrier bars, mechanism for controlling the reciprocation of said bars, balanced pairs of cross girders supporting the respective series of bars so as to adapt each series for movement at normal level and at a lower level, and timing mechanism geared direct to said 105 reciprocation-controlling mechanism so as to control the lifting and lowering movements of said girders, whereby each series of carrier bars is lifted into and lowered from its load-carrying level only when moving at the same synchronized forward speed as the other alternated series of bars, thus enabling the load to be transported uniformly and uninterruptedly by the conveyor 110 without any relative or differential movement between the load and the carrier bars 115 in the direction of load traverse.

3. A conveyor of the reciprocating bar type, comprising two alternated series of carrier bars, cross girders supporting the respective series of bars, rocker arms supporting said girders in balanced pairs so as to adapt each series of bars for movement at normal level and at a lower level, a driving cam roller, a cam groove in said 120 125

roller, mechanism actuated from the same cam groove for separately reciprocating the two series of bars without any relative variation in speed, and timing cam mechanism 5 geared to said driving cam roller so as to actuate said rocker arms for control of the lifting and lowering movements of said balanced girders, whereby each series of carrier bars is lifted into and lowered from its load- 10 carrying level only when moving at the same synchronized forward speed as the other alternated series of bars, thus enabling the load to be transported uniformly and uninterruptedly by the conveyor without any 15 relative or differential movement between the load and the carrier bars in the direction of load traverse.

4. A furnace or the like of the continuous conveyor type, comprising carrier bars arranged in alternated series extending throughout the entire length both of the furnace and of any extensions thereof so as to constitute a continuous hearth, in combination with mechanism for separately reciprocating said alternated series of bars, cross girders supporting the respective series of bars, rocker arms supporting said girders in balanced pairs so as to adapt each series of bars for movement at normal 20 hearth level and at a lower level, and timing mechanism geared to said reciprocation-controlling mechanism so as to actuate said rocker arms for control of the lifting and lowering movements of said balanced girders, whereby each series of reciprocating carrier bars is lifted to and lowered from its load-carrying hearth level only when moving at the same synchronized forward speed as the other series of bars, thus enabling the 25 load to be transported uniformly and uninterruptedly from one end to the other of the hearth without any relative or differential movement between the load and the respective series of carrier bars in the direction 30 of load traverse.

5. A furnace or the like of the continuous conveyor type in accordance with claim 1, including interlocking facing blocks of refractory heat-resisting material attached to 35 the said carrier bars, to thereby provide an insulated high-temperature moving hearth.

6. A conveyor mechanism comprising a pair of cooperating load carrying structures, and means for imparting to each structure 40 in alternating relationship to the other structure upward movement to a predetermined level, longitudinal movement in one direction at said level, subsequent downward movement, and thereafter return longitudinal movement to the starting position, said means being effective to raise each of 45 the structures to the predetermined level prior to lowering of the other structure, to impart to the structure being raised the same longitudinal speed as the other struc- 50

ture by the time the structure being raised has reached the level of the other structure, and to move both structures longitudinally in the same direction and at the same rate of speed during the time that the structures are disposed at the predetermined upper level. 70

7. A conveyor mechanism comprising a pair of cooperating load carrying structures, means for alternately raising said structures 75 to a common level and lowering them below said level, and means for imparting longitudinal movement to each structure in one direction when it is at its upper level and for imparting return longitudinal movement thereto when it is at a lower level, said first mentioned means being effective to raise each supporting structure to the upper level prior to lowering of the other supporting structure to the lower level, and said second mentioned means being effective to impart to each supporting structure as it is raised the same longitudinal speed as the other structure by the time the structure being raised has reached the level of the other 90 structure and to move both supporting structures longitudinally in the same direction and at the same rate of speed when both of said structures are disposed at the 95 upper level. 100

8. A conveyor mechanism as set forth in claim 6 in which the means for imparting longitudinal movement in both directions to both of the load carrying structures comprises a single cam. 105

9. The method of operating a conveyor mechanism of the type comprising separate load carrying structures, which consists in alternately raising and lowering said structures to cause them to alternately support the load, imparting longitudinal load advancing movement to each structure when the same is in a raised position, imparting return longitudinal movement to each structure when the same is in its lowered position, bringing each load carrying structure during its raising movement up to the same longitudinal speed as the other load carrying structure, and moving both structures longitudinally at the same load advancing speed when said structures are in their upper or load transfer and transporting positions. 110
